UNITED STATES PATENT OFFICE.

SAMUEL A. HOLMES, OF STORM LAKE, IOWA.

CRUTCH CHAIR.

Application filed August 21, 1923. Serial No. 658,613.

To all whom it may concern:

Be it known that I, SAMUEL A. HOLMES, a citizen of the United States, residing at Storm Lake, in the county of Buena Vista and State of Iowa, have invented a new and useful Crutch Chair, of which the following is a specification.

This invention relates to a combined crutch and chair and aims to improve generally the construction as shown in my Patent Number 1,433,373, the primary object of the invention being to provide a novel form of crutch provided with a foldable seat structure wherein the seat may be readily and easily moved to its active position.

Another important object of the invention is to provide a device of this character wherein the seat portion may be folded to a position between the legs of the crutch when the seat portion is out of use.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a front elevational view of a crutch constructed in accordance with the invention, showing the chair portion in its inactive position.

Figure 2 is a front elevational view disclosing the chair portion of the crutch in its active position.

Figure 3 is a side elevational view thereof.

Figure 4 is a sectional view taken on line 4-4 of Figure 3.

Figure 5 is a sectional view taken on line 5-5 of Figure 4.

Figure 6 is an enlarged detail view of one of the side members of the chair portion.

Referring to the drawings in detail, the crutch embodies yieldable leg members 5 and 6 respectively which have their upper ends positioned in suitable openings in the arm section 7 thereof, the lower ends of the leg members being normally held together by means of the securing ring 8.

The hand hold is indicated at 9 and has pivotal connection with the leg member 5

at 10, the opposite end of the hand hold being formed with an eye member 11 adapted to be positioned over the hook member 12 carried by the leg member 6, whereby the leg members will be held against lateral movement when the device is to be used as a crutch. A suitable latch member indicated at 13 is adapted to swing downwardly and engage the member 11 to restrict movement of the hand hold 9 while the crutch is being used.

The seat portion includes side bars 14 and 15 which have their inner ends pivotally connected to the securing plates 16 that in turn are secured to the leg members 5 and 6 in a manner to swing with respect to the leg members. Forming a part of the securing plates are inwardly extended end sections 17 that provide supports for the outer ends 75 of the bracing bars 18 that have their inner ends pivotally connected at 19, a locking pin 20 being provided to normally hold the bracing bars in their extended positions.

Pivotally connected to the forward end 80 of the side bar 15 is a forward bar 21 that is formed with an extension 22 adapted to fit in the eye 23 formed at the forward end of the bar 14 so that when the seat section is moved to its active position, the bar 21 85 may be moved to a position as shown by Figure 4, to hold the side bars 14 and 15 against movement with respect to each other.

The reference character 24 indicates leg members which have pivotal connection with the side bars 14 and 15 at 25, the leg members being formed with elongated openings 26 that receive the pins 27 that extend inwardly from the leg members 5 95 and 6, forming a pivot point between the leg members 5 and 6 and leg members 24 to permit the leg members 24 to be folded adjacent to the leg members 5 and 6.

From the foregoing it will be obvious 100 that when the device is to be used as a crutch, the seat portion thereof may be folded to a position as shown by Figure 1 of the drawings, but when the device is to be used as a seat or chair, the hand hold 9 may be disconnected allowing the leg members 5 and 6 to spread.

With the spreading of the leg members 5 and 6, the bars 18 move to positions as shown by Figure 4 holding the leg members 110 5 and 6 in their extended positions. The bars 14 and 15 are now moved downwardly

to a position as shown by Figure 3 of the drawings and the bar 21 moved to hold the side bars 14 and 15 against movement with respect to each other.

5. As the side bars 14 and 15 move to horizontal positions, the leg members 24 move downwardly to cooperate with the leg members 5 and 6 to provide the supporting legs of a chair.

10. It might be further stated that a seat cover indicated at 28 may be secured to the side bars 14 and 15 as by means of the lacing member 29.

What is claimed as new is:—

15. 1. In a device of the character described, a crutch member including leg members, means for connecting the leg members at their upper ends to permit of movement of the leg members, a seat portion including

20. pivoted side bars having connection with the leg members, pivoted bars disposed between the leg members of the crutch and adapted to hold the leg members of the crutch against movement with respect to each other, a bar 25 having connection with the side bars to hold the side bars against movement with respect to each other, and leg members pivotally connected to the seat portion.

20. 2. In a device of the character described, a crutch including leg members, means for connecting the upper ends of the leg members to permit the leg members to move with respect to each other, a seat portion pivotally connected to the leg members and adapted to hold the leg members against movement towards each other, and leg members pivotally connected to the seat portion and cooperating with the leg members of the crutch to hold the crutch in an upright position.

35. 3. In a device of the character described, a crutch including an arm section, yieldable leg members, detachable means disposed intermediate the ends of the leg members for holding the central portions of the leg mem-

bers in spaced relation with each other, means embracing the lower ends of the leg members for holding the lower ends of the leg members together, and a foldable seat section mounted between the leg members. 50

4. In a device of the character described, a crutch including an arm section, flexible leg members secured to the arm section at the upper ends of the leg members, a hand-hold detachably connected with one of the 55 leg members, and carried by the opposite leg member, said hand-hold adapted to normally hold the intermediate portions of the leg members in spaced relation with each other, a foldable chair section supported by 60 the leg members, and means embracing the lower ends of the leg members for holding the lower ends of the leg members in engagement with each other.

5. In a device of the character described, 65 a crutch including an arm section, flexible leg members having their upper ends secured to the arm section, a pivoted member carried by one of the leg members and adapted to be supported between the leg members for holding the central portions of the leg members in spaced relation with each other, pivoted leg members carried by the first mentioned leg members, and adapted to be moved to their extended positions, to provide 75 a chair support with the first mentioned leg members, a foldable chair seat section supported by the leg members, and a securing ring adapted to embrace the lower ends of the first mentioned leg members to normally hold the lower ends of the first mentioned leg members together.

In testimony that I claim the foregoing as my own, I have hereto affixed my signature in the presence of two witnesses.

SAMUEL A. HOLMES.
